Des. 233,858

Patented Dec. 3, 1974

233,858

TYPEWRITER HOUSING WITH TAMBOUR COVER

Karl T. Baughman, Lake Forest, Ill., assignor to
Sears, Roebuck and Co., Chicago, Ill.

Filed June 7, 1973, Ser. No. 367,808

Term of patent 14 years

Int. Cl. D18—01

U.S. Cl. D64—11 A

Fig. 2.

Fig. 3.

Fig. 4.

Fig. 6.

Fig. 5.

FIG. 1 is a front perspective view of a typewriter housing and tambour cover showing my new design;

FIG. 2 is a side elevational view thereof with the handle in retracted position;

FIG. 3 is a top plan view thereof;

FIG. 4 is a front elevational view thereof;

FIG. 5 is a front perspective view thereof with the tambour cover in fully retracted position and with the rear cover element in its retracted position;

FIG. 6 is a front elevational view thereof;

FIG. 7 is a perspective view thereof taken from the left of FIG. 5; and

FIG. 8 is a perspective view thereof from the side opposite of FIG. 7.

The bottom of the typewriter housing is plain and smooth.

I claim:

The ornamental design for a typewriter housing with tambour cover, as shown and described.
